UNITED STATES PATENT OFFICE.

JESSE LOCKHART, OF MACON COUNTY, ILLINOIS.

MOTOR FOR STREET-CARS.

SPECIFICATION forming part of Letters Patent No. 231,183, dated August 17, 1880.
Application filed September 15, 1879.

To all whom it may concern:

Be it known that I, JESSE LOCKHART, a resident of the county of Macon and State of Illinois, have invented certain new and useful Improvements in Motors for Street-Cars and other purposes, of which the following is a true and correct description.

My invention consists in a combination of ratchet and cog wheels connected with the driving-wheels of a car, and operated by a pair of levers which engage the ratchet-wheels alternately, in a manner to be hereinafter set forth.

In the drawings accompanying and forming a part this specification, Figure 1 is an elevation, and Fig. 2 a plan, of my invention, while Fig. 3 is an end elevation of lever-beam by means of which the motion of the driving-levers is made reciprocal.

A is a large cog-wheel rigid on the shaft, with ratchets B B. C is a pinion connected with wheel A and with a cog-wheel on the car-wheel shaft. E E are levers provided with pawls e e on opposite sides of ratchets B B, and connected with lever-beam D by means of rods d d. F F are pedals on levers E E.

In operation the weight of the operator is thrown on either lever alternately, causing a

part revolution in wheel A, and through it to the wheels of the car, at each change of position. The lever-beam D causes one lever to become elevated as the other is depressed, thus making a continuous motion possible.

I am aware that motors have been made with cog-gearing, ratchets, and double pawls, also with the double tread-levers connected with each other by a cord passing over pulleys, and I do not claim such; but

I claim as new and of my invention—

In a car-wheel motor, the combination, with the ordinary frame-work and axles, upon one of which is placed a cog-wheel, of the intermediate pinion, C, the large cog-wheel A, the smaller ratchets B, mounted upon the same shaft with the cog-wheel, the levers E, provided with the pawls e e, one on top and one beneath, and the treads F on the long end of the levers, and the rocking beam D, connected with the levers E by means of the rods d, substantially as shown, and for the purpose set forth.

JESSE LOCKHART.
